DESIGN.

—o—

J. L. FOLSON.

CARPET.

No. 17,603.

Patented Aug. 9, 1887.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 17,603, dated August 9, 1887.

Application filed July 6, 1887. Serial No. 243,552. Term of patent 3½ years.

To all whom it may concern:

Be it known that I, JAMES L. FOLSOM, of Brooklyn, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

15 The main feature of my design is the figure

A, which is repeated over the surface of the carpet, as shown in the photograph. Figure A consists of two scroll forms interlocked with each other, making a sort of double scroll figure. These figures are placed upon a suitable ground.

What I claim as new, and desire to secure by Letters Patent, is—

The design for carpets, consisting of the design substantially as shown.

JAS. L. FOLSOM.
